UNITED STATES PATENT OFFICE.

ENOCH RECTOR, OF NEW YORK, N. Y., ASSIGNOR TO RECTOR ENGINE CORPORATION,
OF NEW YORK, N. Y., A CORPORATION OF NEW YORK.

STEAM-GENERATOR.

1,132,617.

Specification of Letters Patent. Patented Mar. 23, 1915.

Application filed January 3, 1911, Serial No. 600,430. Renewed Aug. 11, 1914. Serial No. 856,288.

To all whom it may concern:

Be it known that I, ENOCH RECTOR, a citizen of the United States, residing in the borough of Manhattan of the city of New York, in the State of New York, have invented certain new and useful Improvements in Steam-Generators, of which the following is a specification.

My invention relates particularly to generators adapted to produce steam under relatively high pressure and consists in the new and novel features of construction and combinations of parts hereinafter set forth and claimed.

15 In the accompanying drawings: Figure 1 is a side elevation in section of a steam generator embodying my invention. Fig. 2 represents a plan view of the same partly in section. Fig. 3 represents a plan view partly 20 in section of another form of my improved steam generator. Fig. 4 represents a side elevation partly in section of a generator embodying the construction indicated in Fig. 3.

25 The steam is generated by heat supplied from a burner 1, indicated diagrammatically, of any desired construction to supply a large number of heat units and is preferably arranged at the bottom of a casing 2 which may be formed of or lined with any suitable insulating material such as asbestos 2^a, the said casing being provided at its top with an outlet 3 for the gases of combustion. The generator 4 preferably comprises a receptacle, which is preferably made in two parts, one of said parts preferably being a base plate 5 of any desired section, and the other part being a dome 6 secured to the base plate in any suitable manner as by the 40 screws 7 or by being welded thereto.

Secured to the base plate are a plurality of projections 8 which extend into the generating chamber or water space of the generator. Said projections are preferably 45 conical in shape and may be formed integral with the base plate if desired, or the same may be secured thereto in any suitable manner as by being provided with threaded stems 9 engaging in a tapped socket 10 provided in the base plate. If desired a plurality of radial ribs 11 may be provided extending between the successive projections thus dividing the projections into a plurality of sections, the said sections however be-

ing in communication with each other adjacent to the wall of the generator.

The water is admitted to the generator through a suitable pipe 12 which preferably extends to a suitable point below the tops of the projections and below the normal water level of the generator. The steam is conducted from the generator by a suitable pipe 14 which communicates with the top thereof.

In order to increase the heating capacity the side walls of the generator may be provided with a plurality of corrugations or ribs 15. The inside of the generator wall may be also provided with depending ribs or flanges 16 which extend downward into the generator chamber. Preferably also the bottom of the base plate is provided with a plurality of hollow conical shaped projections 17 to increase the heating surface.

While generating steam the water is not permitted to rise above the tops of the projections extending into the generating chamber but is normally kept a considerable distance below the top thereof. The projections or extensions act as heat conveyers and produce a continuous circulation of the water which is contained in the small communicating compartments formed by the bases of the adjacent projections. The steam which is formed on the bottom tends to follow the metal and rises alongside the projections until it is liberated above the level of the water and in passing along the sides of the projections the friction of the steam tends to carry particles of the water with it thus producing a constant movement or circulation.

By means of this construction an extremely simple and efficient generator is provided which can be made from simple castings and with very little fitting or packing of any kind. The efficiency is extremely high owing to the very large amount of heat absorbing and radiating surface relative to the total quantity of water contained in the generator at any one time and owing also to the continuous circulation of the water which is caused by the rising steam.

Although I have shown and described the generator as constructed and used to produce steam under pressure, it is obvious that it may be used to heat water or for any other similar purposes. If it is used solely for heating water, it is not necessary to main-

tain the water level below the tops or apexes of the projections, but the water may entirely fill the chamber. In this case also, as in the generation of steam, the projections 5 serve as circulation producing means and induce and maintain a constant circulation within the generating chamber, thus facilitating the absorption of heat. It is obvious also that various changes within the knowledge of those skilled in the art may be made 10 in the details thereof without departing from the spirit of the invention provided the means set forth in the following claims be employed.

15 I claim as my invention:

1. A generator comprising a generating chamber having a plurality of projections extending from the bottom thereof and terminating within the generating chamber at 20 a point above the water level of the generator.

2. In a generator the combination with one of the walls of the generator, of a plurality of circulation producing projections 25 extending above the normal water level of the generator and terminating within the generator slightly above the normal water level thereof.

3. In a steam generator comprising a generating chamber, a plurality of conical shaped projections extending partly in the water and partly above the normal water level of said generating chamber and terminating within the generating chamber.

35 4. In a steam generator comprising a generating chamber, the combination of a plurality of projections terminating within the generating chamber and extending partly in the water and partly above the normal water 40 level, and means for admitting water near the base of said projections.

45 5. In a steam generator, the combination with a bottom plate having a plurality of vertical projections, of a plurality of radial ribs extending from the center of said plate toward the circumference of the generator to divide said plate into a plurality of sections, said sections having communication with each other adjacent to the wall of the 50 generator.

55 6. In a steam generator comprising a base and a cap portion secured together to form a generating chamber, a plurality of projec-

tions extending upward from the base plate into the generating chamber and terminating within the generating chamber, and a plurality of projections extending downward from said cap portion into the generating chamber and terminating above said projections.

60 7. In a steam generator comprising a base plate and a cap portion secured together to form a generating chamber, a plurality of projections secured to the base plate extending into the generating chamber and terminating above the normal water level, an inlet pipe for supplying water at the base of said projections and below the normal water level of the chamber, an outlet pipe secured to the cap portion and means secured to the base plate for increasing the heating surface thereof.

70 8. In a generator the combination with one of the walls of the generator, of a plurality of circulation producing projections 75 extending above the normal water level of the generator and terminating within the generator slightly above the normal water level thereof, the exposed heating surface of the projections above the water level increasing as the water level is lowered at a greater rate than the rate of lowering of the water level.

75 9. A generator comprising a generating chamber having heat carrying projections 80 extending from opposite sides of one of the walls thereof, the external projections adapted to be subjected to the direct heat from a heating means and the internal projections terminating within the generating 85 chamber at a point above the water level in the generator.

90 10. A generator comprising a generating chamber having a plurality of projections extending from the bottom thereof and terminating within the generating chamber at a point above the water level of the generator and conical heating projections extending from the exterior side of said bottom.

95 This specification signed and witnessed 100 this 28th day of December A. D. 1910.

ENOCH RECTOR.
